AUTOMATIC CARTON SETTING-UP
MACHINEMartin Burger, Morris, Ill., assignor to Self-Lock-
ing Carton Company, Chicago, Ill., a corpora-
tion of IllinoisApplication March 3, 1932, Serial No. 596,457
Renewed August 22, 1936

25 Claims. (Cl. 93—37)

The present invention relates to a device for erecting or "setting up" foldable cartons of the type having cell-forming partitions extending transversely of the carton when in erect position.

5 In my copending application, Serial No. 545,788, filed June 20, 1931, of which the present application constitutes a continuation in part, is described a machine for automatically setting up cartons, particularly cartons of the type described in Troyk Patent No. 1,766,155.

A principal object of the present invention is to provide a device for erecting collapsible egg cartons of the type described in Benoit Patent No. 1,768,024.

15 An additional object is the provision of a machine for continuously or automatically setting up cartons of the type described.

These and other objects will be seen in the following description and drawings, in which

20 Fig. 1 is a top view of a machine constructed in accordance with my invention;

Fig. 2 is a sectional view taken along line 2—2 of Fig. 1;

Fig. 3 is an end view of the machine shown in Fig. 1;

Fig. 4 shows a collapsed carton of the type adapted to be set up by my machine; and

25 Figs. 5 and 6 are detail views of the setting up mechanism in various positions of operation on a carton.

The egg carton A, as shown in the drawings, has a continuous wall structure formed from a single blank of paper having a folded central portion which forms a longitudinal partition B. A plurality of aligned openings C extend through the outer wall sections and the longitudinal partition. Transverse cell-forming partitions D are extended half their length through the openings in the longitudinal partition. When the carton 30 is in the collapsed position shown in Fig. 4, these transverse partitions are pivoted about their central portion and lie in a position parallel to the walls of the carton.

As shown in Figs. 1 and 2 the frame structure 45 of the machine has a table portion 10 thereon. A hopper 11, which is designed to receive a stack of folded or collapsed cartons of the type described, is mounted on one end of the table. The front side of the hopper has an opening 12 in its lower portion which allows the escape therefrom of the lowermost carton of the stack.

Extending longitudinally of the platform 10 and on the under side thereof are two rods 13 upon the rear portion of which is slidably mounted a dog 14. This dog has an upward extension

which travels in a central longitudinal opening in the table 10 and operates to engage the rear portion of the lowermost carton in the hopper 11, causing the carton to move forward through the opening 12.

5 The dog 14 projects the front end of the carton a sufficient distance from the hopper to be engaged by a driven friction roller 15 which is mounted on the platform in the path of travel of the carton, thereby causing the carton to move 10 along the table and completely out of the hopper.

The rods 13 also carry a slidably mounted and longitudinally extending bar 16 which has a dog 17 on its rear end and a similar dog 18 on its front end. These dogs are loosely pivoted and preferably counterweighted so that their forward ends or noses tend constantly to rise above the top of the table, but will yield in the manner of a trailing pawl during the back stroke of the bar 16. During its forward stroke the rear dog 17 20 engages the rear of the carton and pushes it forward to substantially the position shown by the carton A in Fig. 2. When this position is reached the bar 16 retracts its movement and another carton is picked up by the rear dog 17 on its next 25 forward movement.

Movement of the bar 16 to its backward position causes the front dog 18 to engage the rear of the carton from the position in which it was left by the rear dog 17, and upon forward motion of the bar, the front dog pushes the carton to a position beneath the setting-up plunger to be described hereinafter.

Cyclic operation of the dogs 14, 17 and 18 and rotation of the friction roller 15 thereby 30 continuously supplies the setting-up mechanism with cartons.

As the folded carton emerges from the friction roller 15 it encounters the point of a transverse cover-opening rod 19 which enters between the two cover portions of the carton and, during the travel of the carton along the table, rotates the upper cover portion through 180° and into horizontal position against the table. It will be seen from Figs. 1, 2 and 3 that this rod extends along 40 the path of travel of the carton and transversely thereof, being anchored adjacent the forward end of the table. Rotation of the cover into open position causes the longitudinal partition of the carton to assume the vertical position shown by 45 the carton A in Fig. 2. The cover-opening rod is bowed upwardly in its central portion to permit passage thereunder of the vertical longitudinal partition. This bowed portion also materially assists in rotating the cover into open po- 50 55

sition since its leverage on the cover is greater than if the rod was flat.

During rotation of the upper cover into open position the lower cover portion is maintained flat against the table by the guide 20 under which it passes, as shown in Fig. 1. The opposite side of the table is provided with a guide 21 which limits the transverse movement of the rotated cover portion.

10 In addition to the dogs 17 and 18, the bar 16 carries a central carton support 22 which forms a traveling carrier for the carton. Upon forward motion of the bar 16, the carton A is carried, by support 22 and dog 18, from the position shown 15 in Fig. 2 forwardly into the setting-up mechanism.

The setting-up mechanism includes two spaced platforms 24 and 25 which receive the outer or cover-forming portions of the carton walls. Co-operating with these platforms are two pairs of grippers 26 and 27, respectively, which rotate about shafts 77 and 80 to contact the cover-forming portions of the carton and to firmly hold the same against the platforms. The platforms and grippers are slidably mounted on horizontal bars 28 and 29, and are movable as units toward and from the center of the machine.

Positioned above the space between the platforms 24 and 25 is a longitudinally extending plunger 30. This plunger is similar in structure to the device described in my copending application Serial No. 576,265, filed November 20, 1931, and is carried by and is slidably arranged upon two vertical posts 31. The plunger consists of a head of a size corresponding to the size of the interior of the erected carton, and has a series of slots arranged to accommodate the longitudinal partition B and the transverse cell-forming partitions D.

When the carton is pushed onto the platforms 40 24 and 25 the plunger is above and spaced from the carton. The platforms are provided with stops 33 which limit the forward travel of the carton and stops 34 which center the carton beneath the plunger. As the carton enters the setting-up mechanism the platforms 24 and 25 approach the center of the machine until the outer edges of the carton walls abut the stops 34. At this position the grippers 26 and 27 engage the cover along the inner edges of the platforms 24 and 25. This line of engagement of the carton 50 is preferably scored and forms the line of division between the side walls of the carton and the cover portions. The platforms and grippers are then moved away from each other to a position as shown in dotted lines in Fig. 5, causing the 55 lower portion of the upwardly extending longitudinal partition B to be separated from a point G above which the two layers of the partition are held together by the cross partitions. Separation of the lower portions of the layers of the 60 longitudinal partition B causes the transverse cell-forming partitions to swing into a position substantially at right angles to the longitudinal partition and in a position to be received by the transverse slots of the plunger 30. It will be seen 65 that the plunger acts to perfect the alignment of the transverse partitions with the slots in the carton wall structure.

When the grippers 26 and 27 have engaged the outwardly extending cover portions so as to fix 70 the position of the carton, the bar 16 is retracted, thereby again moving the carton support 22 toward the position shown in Fig. 2.

The plunger 30 is lowered into engagement with the carton and continues its downward movement to the position shown in Fig. 6. With this

continued downward movement of the plunger the platforms and grippers again approach the center of the carton, causing the carton walls to be rotated with respect to the cross partitions. A score F is provided in the lower portion of 5 the carton walls and forms the apex of a V-shaped channel on each side of the longitudinal partition. As the walls rotate, the bottom of the transverse partitions pass through the slots C in each of the carton walls. The downward movement of the plunger is continued until the slots C pass over hooks E on the transverse partitions D of the carton. The grippers are then released from engagement with the top-forming portions 10 of the carton, and the resilience of the carton 15 walls causes the upper end of slots C to snap into engagement with hooks E, thereby completing the setting-up operation. The plunger then moves upwardly into its original position, the platforms and grippers return to their original 20 position, and the set-up carton falls through the space between the platforms to be received by a suitable continuous belt conveyor 35.

It will be understood that cyclic operation of this mechanism, which may be effected in any 25 suitable manner, results in the rapid and automatic erection of cartons.

In the modification shown in the drawings rotation is imparted to the shaft 40 by any suitable means such as the motor and reducing gears 30 (not shown). A cam arrangement 41 is mounted on the shaft and acts through pin 42 to raise and lower the lever 43 which has an intermediate portion pivoted about the fixed shaft 44. Downward movement of the pin 42 causes the arm 45 of the 35 lever to be raised, whereby the bell crank 46 is rotated about the fixed shaft 47 in a counterclockwise direction. The upper arm of the bell crank 46 has a slot 48 which engages a corresponding pin on the dog 14. Counterclockwise 40 motion of the bell crank 46 causes the dog 14 to move backwardly, and clockwise rotation of the bell crank, caused by the downward movement of arm 45, causes the dog 14 to move forwardly.

The gear 50 fixed to shaft 40 drives the shaft 45 52 by means of gear 51. Also mounted on the shaft 52 is a disc 53 provided with a pin 54 adjacent its outer portion. The pin 54 slidably engages a slot in the sleeve 55 of lever 56. The bar 16 is connected through lever 57 with lever 56, and rotation of the disc 53 causes the bar 16, 50 carrying dogs 17 and 18 and carton support 22, to be moved in a forward direction and then in a backward direction.

A sprocket wheel 58 is fixed to shaft 40 and rotates the pressure roller 15 by means of a chain 55 59, sprocket wheel 60 and shaft 61.

A beveled gear 62 on the shaft 52 imparts rotation to the longitudinal shaft 64 by means of a second beveled gear 63.

To the outer end of the shaft 64 is fixed a 60 sprocket wheel 65 which by means of chain 66 drives sprocket wheel 67. The sprocket wheel 67 rotates a shaft 68 which extends parallel to the shaft 64. Shafts 64 and 68 are provided with 65 cams 69 and 70, respectively, which raise and lower the upwardly extending bars 71 and 72. The bar 72 is connected to a head 73 which is provided on its inner face with a horizontal slot 74 into which the pin 75 is engaged. When the 70 bar 72 and head 73 are lowered by the rotation of the sprocket wheel, the lever 76, which engages the pin 75, is depressed. The lever 76 and the grippers 27 are fixed to a shaft 77 so that depression of the lever causes the grippers to be 75

5 depressed into contact with a carton on the platform 25. The upwardly extending bar 71 is raised and lowered by rotation of the cam device 69 and depresses and raises the grippers 26 in a manner corresponding to the movement of grippers 27. The upwardly extending bar 71 is provided with a head 78 having a horizontal slot registering with a pin on the lever 79, thereby providing means for rotating shaft 80 to which 10 the grippers 26 are fixed.

10 The platform 25 and grippers 27 are slidably arranged on the horizontal bars 29 and are held by frame structure 81.

15 Affixed to shaft 64 is a cam 82 which operates the lower arm of a bell crank 83, pivoted about the shaft 84. The upper arm of the bell crank is secured to the frame structure of the platform 24 at 99. Clockwise rotation of the bell crank causes the platform to be moved away from the 20 center of the carton, and the counterclockwise rotation of the bell crank causes the platform and grippers to move toward the center of the carton.

25 A pivoted rod 85 extends from the frame structure of the platform 24 to the lower arm of a bell crank 86 which rotates about shaft 87. The upper arm of the bell crank has an inwardly extending pin which engages a slot in the frame structure of the platform 25. As the platform 24 moves inwardly the rod 85 rotates the bell crank 30 86 in a clockwise manner, causing the platform 25 and grippers 27 to likewise move inwardly. The action of the platforms and grippers on each side of the plunger is thereby made synchronous and similar.

35 The lever 43 has its end pivotally connected to an upwardly extending lever 90. The upper end of the lever 90 is attached to a rear extension on the plunger support 91. The plunger support 91 is slidably mounted on the two vertical bars 40 31, the bars being supported at their upper end by bracket 92 and at their lower end by bracket 93.

45 The inner sprocket wheel 94 mounted on the shaft 64 rotates, by means of chain 95 and sprocket wheel 96, the roller 97 which has mounted thereon the continuous belt 98. The belt is so arranged that cartons from the setting-up mechanism thereabove fall upon the belt and are carried away.

50 In operation, rotation of the shaft 40 causes forward movement of the dog 14, whereby a carton is pushed beneath the friction roller 15. The friction roller 15 causes the carton to be moved outwardly in engagement with the cover opening rod 19. Continued movement of the shaft 40 causes the rod 16 to be thrust forwardly whereby the carton is advanced to its second position as shown by carton A of Fig. 2. The arm 16 is then retracted until the dog 18 engages the rear of the carton. The bar is then advanced and the carton, resting on the support 22, is thrust beneath the raised plunger 30. Rotation of the shaft 64 causes the platforms and grippers to cooperate in centering the carton, in gripping the cover portions thereof, and in stretching the horizontal walls of the carton outwardly to rotate the transverse partitions into planes substantially at right angles to the longitudinal partition. The lever 43 then causes the plunger 30 to be lowered into interlocking relation with the partitions of the carton. Before the plunger 30 reaches the plane of the outstretched carton walls, the carton support 22 is 70 drawn backwardly by the bar 16. The plunger 75

continues its downward travel and the grippers and platforms are moved inwardly, whereby the walls of the carton are rotated into interlocking relation with the hooks E of the transverse partitions. Continued movement of the operating 5 mechanism causes the grippers, platforms and plunger to be returned to their original positions for operation upon the next carton.

10 The above described device is susceptible to modification and those changes which come with- 10 in the spirit of my invention are intended to be included in the appended claims.

I claim:

1. In a device for setting-up cartons of the type having a longitudinal partition provided with 15 hinged cross partitions and side walls having slots to receive said partitions, feeding means for delivering said cartons one at a time, means for distending the walls of one of said cartons outwardly and for rotating the hinged cross partitions 20 into alignment with the openings in the carton walls, and means for moving said slotted wall into engagement with said cross partitions.

2. In a device for setting-up cartons of the type having a longitudinal partition provided 25 with hinged cross partitions and side walls having slots for receiving and interlocking with said cross partitions, a hopper for receiving a stack of collapsed cartons, a traveling dog for delivering a collapsed carton from said hopper, means 30 for continuing the travel of said carton, a cover-lifting rod having a point for entering between the collapsed walls of said carton, said rod extending across the path of travel of said carton, and having a raised central portion, grippers for 35 receiving the walls of said carton, means for moving said grippers toward and away from each other, a plunger arranged above said grippers, said plunger being of substantially the same shape as the interior of an erected carton and having notches for receiving the longitudinal and cross partitions of said carton, and means for raising and lowering said plunger.

3. In a device for setting-up cartons of the type having a longitudinal partition provided 45 with hinged cross partitions and side walls having slots for receiving and interlocking with said cross partitions, means for continuously feeding collapsed cartons one at a time, means for distending the walls of said carton and for positioning said cross partitions in alignment with the slots in said walls, and means for moving said wall into interlocking engagement with said cross partitions.

4. In a device for setting-up collapsed cartons 55 of the type described, comprising a hopper for receiving a stack of collapsed cartons, means for delivering cartons from said hopper, means for rotating one side of said collapsed carton into open position, and means for distending the 60 walls of said carton and for rotating the same upwardly into engagement with the cross partitions of said carton.

5. In a device for setting-up cartons of the type having a longitudinal partition provided 65 with hinged cross partitions and side walls having slots for receiving and interlocking with said cross partitions, means for rotating the walls of a collapsed carton into open position, grippers for engaging the walls of said carton, means for 70 moving said grippers toward and away from each other, and a plunger arranged above said grippers, said plunger being operable to depress said longitudinal partition.

6. In a device for setting-up egg cartons of the 75

- type having a longitudinal partition provided with hinged cross partitions and side walls having slots for receiving and interlocking with said cross partitions, spaced platforms, means for delivering an opened carton to said platforms, grippers for engaging the walls of said carton against said platforms, means for moving said platforms toward and away from each other, a plunger above the space between said platforms, means for raising and lowering said plunger and means for releasing said grippers. 5
7. In a device for erecting cellular cartons of the type having walls and longitudinal partition sections provided with a plurality of separate cross partitions pivotally positioned at their central portions in slots in said longitudinal partition sections, erecting means including means for initially opening the walls of a collapsed carton, means for maintaining the separate cross partitions in position substantially at right angles to said walls, and means for producing relative movement between said walls and said cross partitions whereby to produce an interlock between notches in said walls and interlocking elements 10 in the outer portions of said cross partitions. 15
8. In a device for erecting cellular cartons of the type having a body portion folded on itself to form a double longitudinal partition and walls and a series of separate cross partitions pivotally positioned in slots in said longitudinal partition, setting-up mechanism including means for initially opening the walls of the body portion of the carton, means for spreading the portions of said double longitudinal partition apart, and 20 means for producing relative movement between the walls of the carton and the cross partitions whereby to produce an interlock between notches in said walls and interlocking portions on said cross partitions. 25
9. In a machine for erecting cellular cartons of the type having a body portion folded upon itself to form a double walled longitudinal partition and walls and separate cross partitions pivotally positioned in slots in said longitudinal partition, setting-up mechanism including means for feeding collapsed cartons, means for initially opening the walls of said carton, and means for producing relative motion between said walls and said cross partitions to produce an interlock between notches in said walls and interlocking portions on said cross partitions. 30
10. In a machine for erecting cellular cartons of the type having a body portion folded upon itself to form a double walled longitudinal partition and walls and separate cross partitions pivotally positioned in slots in said longitudinal partition, setting-up mechanism including means for feeding collapsed cartons, means for initially opening the walls of said carton, means for spreading apart the walls of said longitudinal partition, means for maintaining said cross partitions in position for interlock with the walls of said carton, and means for producing relative motion between said carton walls and said cross partitions to produce an interlock between notches in said walls and interlocking portions on said cross partitions. 35
11. In a machine for erecting cellular cartons of the type having a body portion folded upon itself to form a double walled longitudinal partition and walls and separate cross partitions pivotally positioned in slots in said longitudinal partition, setting-up mechanism including means for moving the walls of the carton outwardly, means for moving the longitudinal partition 40
- downwardly and means for simultaneously moving said walls inwardly to produce an interlock between said walls and the cross partitions of the carton. 45
12. In a machine for erecting cellular cartons of the type having a body portion folded upon itself to form a double walled longitudinal partition and walls and separate cross partitions pivotally positioned in slots in said longitudinal partition, setting-up mechanism including means for feeding a collapsed carton, means for initially opening the walls of said carton, means for maintaining the cross partitions of the carton in position for interlock with the carton walls, and means for moving the walls of the carton into erect position in interlocked relation with said cross partitions. 50
13. In a machine for erecting cellular cartons of the type having a body portion folded upon itself to form a double walled longitudinal partition and walls and separate cross partitions pivotally positioned in slots in said longitudinal partition, setting-up mechanism including a hopper for a stack of collapsed cartons, a conveyor for feeding cartons from said hopper, means for initially opening the walls of said carton, and additional means for moving said initially opened walls into interlocked relation with respect to the cross partitions of said carton. 55
14. In a device of the type described, means for feeding a carton blank, an oblique guide bar in the path of travel of said blank for moving the walls thereof at least partially in position for receiving cross partitions, and means for inserting cross partitions into slots in said blank. 60
15. In a device of the type described, a hopper for a stack of carton blanks, means for feeding said cartons from said hopper, receiving means for positioning a blank for further operations, a presser head member operable upon a vertical post for bending said blank along intermediate score lines, finger members to bend said blank along marginal score lines, and assembling means including means for causing cross partitions to engage slots in said blank. 65
16. In a device for erecting cellular cartons of the type having a longitudinal partition provided with a series of separate cross partitions rotatably positioned in slots therein, slotted walls joined to said longitudinal partition for interlocking with notched edges of said cross partitions and cover forming sections joined to said walls, the combination of gripper elements for engaging the cover forming sections, means for moving said grippers away from each other after engagement of the cover forming sections of a carton and then toward each other, and means for producing relative vertical motion between said partitions and said grippers when the latter move toward each other to produce an interlock between the slots in said walls and the notched edges of said cross partitions. 70
17. In a device for erecting cellular cartons of the type having a blank folded upon itself to form a doubled longitudinal partition, slotted walls and cover forming sections and separate cross partitions pivotally positioned with respect to said longitudinal partition and having edge notches adapted to interlock with said slotted walls, the combination of means operable upon said cover forming sections for moving the latter outwardly and then inwardly in substantially the same plane, and means for producing relative vertical movement between said partitions and said cover forming sections upon the inward 75

movement of the latter to engage said slotted walls with said edge notched cross partitions.

18. In a device for erecting cellular cartons of the type having a blank folded upon itself to form a doubled longitudinal partition, slotted walls and cover forming sections and separate cross partitions pivotally positioned with respect to said longitudinal partition and having edge notches adapted to interlock with said slotted walls, the combination of gripper means for engaging only the cover forming sections and for providing alternate outward and inward movement thereof in substantially a horizontal plane, and means for producing relative vertical movement between said cover forming sections and said partitions during the inward movement of said sections to engage said slotted walls with said edge notched cross partitions.

19. In a device for erecting cellular cartons of the type having a blank folded upon itself to form a doubled longitudinal partition, slotted walls and cover forming sections and separate cross partitions pivotally positioned with respect to said longitudinal partition and having edge notches adapted to interlock with said slotted walls, the combination of spaced platforms positioned to receive the cover forming sections of an opened carton, grippers for engaging said sections against said platforms, means for initially moving said platforms away from each other and then for moving said platforms toward each other, and means for producing relative vertical movement between said partitions and said platforms during the inward movement of the latter to engage said slotted walls with said edge notched cross partitions.

20. In a device for erecting cellular cartons of the type having a blank folded upon itself to form a doubled longitudinal partition, slotted walls and cover forming sections and separate cross partitions pivotally positioned with respect to said longitudinal partition and having edge notches adapted to interlock with said slotted walls, the combination with means for engaging the cover forming sections of said carton, means for moving said engaging means outwardly from an initial position to spread the lower portion of said longitudinal partition and then inwardly to a position closer together than said initial position, and means for depressing said partitions simultaneously with the inward movement of said grippers.

21. In a device for erecting cellular cartons of the type having a blank folded upon itself to form a doubled longitudinal partition, slotted walls and cover forming sections and separate cross partitions pivotally positioned with respect to said longitudinal partition and having edge notches adapted to interlock with said slotted walls, the combination of means for engaging the outer portions of said blank, means for moving said engaging means outwardly until said cross partitions are substantially at right angles to said longitudinal partition and thereafter for moving said engaging means inwardly, and means for depressing said partitions during the inward movement of said engaging means.

22. In a device for erecting cellular cartons of

the type having a blank folded upon itself to form a doubled longitudinal partition, slotted walls and cover forming sections and separate cross partitions pivotally positioned with respect to said longitudinal partition and having edge notches adapted to interlock with said slotted walls, the combination of means for initially opening said blank, a central support for the opened blank, means on opposite sides of said support for engaging the cover forming sections of said carton, means for moving said engaging means initially outwardly and then inwardly, means for depressing said partitions during said inward movement, and means for moving said support to allow for said depression.

23. In a device for erecting cellular cartons of the type having a blank folded upon itself to form a doubled longitudinal partition, slotted walls and cover forming sections and separate cross partitions pivotally positioned with respect to said longitudinal partition and having edge notches adapted to interlock with said slotted walls, the combination of a hopper for folded cartons, means for feeding said cartons from said hopper, means for initially producing relative rotation of the walls of the carton to open the same, means for transferring the opened carton to a position for erection, means engaging the cover forming portions of the carton for moving the same outwardly in a divergent manner thereby to rotate said cross partitions into positions substantially at right angles to said longitudinal partition, said engaging means then being operable to move inwardly toward each other, and means for depressing said partitions during the inward movement of said engaging means.

24. In a device for erecting cellular cartons of the type having a blank folded upon itself to form a doubled longitudinal partition, slotted walls and cover forming sections and separate cross partitions pivotally positioned with respect to said longitudinal partition and having edge notches adapted to interlock with said slotted walls, the combination of a central support for positioning an opened carton, means on opposite sides of said support and independent thereof for engaging said cover forming sections, means for moving said engaging means outwardly in a divergent manner and then inwardly in a convergent manner, means for moving said support away from said carton, and means for depressing the central portion of said carton during the inward movement of said engaging means.

25. In a device for erecting cellular cartons of the type having a blank folded upon itself to form a doubled longitudinal partition, slotted walls and cover forming sections and separate cross partitions pivotally positioned with respect to said longitudinal partition and having edge notches adapted to interlock with said slotted walls, the combination of engaging means operable upon outer partitions of an opened carton for pulling said walls apart in substantially a horizontal plane and then for moving said walls inwardly, and means for depressing the central partition of said carton during said inward movement.

MARTIN BURGER.
